UNITED STATES PATENT OFFICE.

HORACE CATLIN, OF BURLINGTON, IOWA, ASSIGNOR OF ONE-HALF TO
OSWALD HIRSCH, OF SAME PLACE.

CLOTHES-LINE HOLDER.

SPECIFICATION forming part of Letters Patent No. 591,795, dated October 12, 1897.

Application filed June 24, 1896. Serial No. 596,797. (No model.)

To all whom it may concern:

Be it known that I, HORACE CATLIN, a citizen of the United States, residing at Burlington, in the county of Des Moines and State of 5 Iowa, have invented a new and useful Improvement in Clothes-Line Holders, which improvement is fully set forth in the following specification and accompanying drawings.

My invention relates to that class of clothes-line fasteners having a pivoted lever hinged to a boss adapted to clamp the line and turn in direction of pull.

The object of my invention is to simplify and cheapen the cost of manufacture of such 15 fasteners; also to provide a novel construction whereby the clothes-line may be more readily handled for tightening or attaching and detaching, and at the same time to afford a better grip for the clamp.

It is also my object to provide means in a 20 hinged fastener for bracing the fastening-screw against a side or oblique pull, which often causes breakage or loosening of said screw.

In the accompanying drawings, forming a 25 part of this specification, Figure 1 is a side elevation showing my fastener in operative position. Fig. 2 is a front elevation of the same, and Fig. 3 is a detail view of the clamp-ing-lever.

Referring more particularly to the drawings, 1 denotes a disk-shaped bracket having a flat bearing-surface upon its inner side and provided with a boss cast integral therewith 35 upon its outer side.

2 denotes a fastening-screw having its head cast flush with the flat surface of the bracket.

A denotes the body of the fastener, provided with ears a a, adapted to span the boss and having perforations which register with the perforation in said boss.

a' denotes a rounded shoulder formed on the face of the body portion and projects outwardly therefrom.

3 denotes a curvilinear lug formed integral with the body portion and projects downwardly and outwardly therefrom.

4 denotes a lever pivoted to one side of said 50 body portion by a bolt 5. Said lever is pro-

vided at its upper and lower end with laterally-extending yokes, the upper one projecting above and rearwardly of the shoulder a' and the lower yoke adapted to span or embrace the lower end of the lug 3. As shown 55 in Figs. 1 and 3, the lever is formed with an inward bend or curve, the purpose of which is to clear it from the shoulder a' and to allow free access to the clothes-line between the two yokes, as hereinafter described. 60

My line-fastener is secured in position by the screw 2, which should be screwed in until the flat surface of the disk bears tightly against the surface of the fence or wall. This flat surface acts as a brace for protecting said 65 screw when the pull upon the line is oblique or sidewise and swings the body portion at an angle to the screw.

The clothes-line is first passed over the upper yoke of the lever and drawn taut with one 70 hand, the other hand taking up the slack. The upper end of the lever is then pressed back until it jams the line between it and the shoulder. The slack line is then passed under the lower yoke and the upper end of 75 the lever allowed to swing forward. This causes the lower yoke to bind the line between it and the lug 3. To tighten the line at any time, it is grasped between the two yokes and pulled taut, at the same time pressing the 80 upper yoke back to hold the line against the shoulder until the slack can be passed under the lower yoke and jammed between it and the lug 3. It is evident that by securing the lever to one side of the body portion I am 85 enabled to afford ready access to the line for tightening the same without removing it from either yoke. Again, this construction greatly facilitates attaching and detaching the line. Moreover, the shoulder placed between the 90 two yokes affords a rounded surface, over which the line draws, giving it a turn and affording the clamping-lever a better hold.

It is evident the clothes-line may be tightened at any time with one hand. This is accomplished by pulling outwardly and downwardly on the line below the lower yoke sufficiently to release the line from the pressure against the lug 3, yet without throwing the upper yoke all the way back. This allows 95 100

the line to slide freely through the upper yoke and down over the shoulder until the line is drawn taut.

Having shown and described my invention,
5 what I claim, and desire to secure by Letters Patent, is—

In a clothes-line holder, the combination of the body portion having a shoulder projecting outwardly from its face and a depending lug below said shoulder, of a bent lever pivoted to one side of said body portion in rear

of said shoulder provided with laterally-extending yokes which cross said body portion above and below said shoulder substantially as described.

In testimony that I claim the foregoing I have hereunto set my hand, this 1st day of April, 1896, in the presence of witnesses.

HORACE CATLIN.
